UNITED STATES PATENT OFFICE

2,548,781

RESILIENT CLASP

William L. Goodman, Jr., Highland Park, Ill., assignor to Platt Luggage, Inc., Chicago, Ill., a corporation of Illinois

Application January 31, 1947, Serial No. 725,539

4 Claims. (Cl. 292—129)

1

The present invention relates to hand luggage and has for its primary object the provision of a new and improved partition clasping arrangement.

Luggage of various types are provided with partitions for separating clothes and other goods which may be carried in the luggage. The partitions are usually somewhat flexible in character and various means have heretofore been utilized for clasping or securing them to other parts of the luggage, such as the jaw frames.

It is an object of the present invention to provide a new and improved resilient clasp for detachably securing a luggage partition, as to the jaw frame of the luggage.

A further object of the present invention is to provide a new and improved resilient clasp which can be constructed easily and economically and which is readily manipulatable by the user for the purpose of securing or releasing the partition.

A further object of the present invention is to provide a new and improved resilient clasp including a pair of relatively movable members urged into telescoped relation by a single spring which is held in place and guided in novel manner by cooperating portions of the two members, and which clasp is easily secured to the partition and releasably associated with the jaw frame of the luggage.

Other objects and advantages of the present invention will become apparent from the ensuing description of a preferred embodiment thereof in the course of which reference is had to the accompanying drawings, in which:

Fig. 1 is a fragmentary side elevational view of a pair of clasps constructed in accordance with the present invention and shown yieldably securing a partition to a jaw frame of a piece of luggage;

Fig. 2 is an enlarged cross sectional view taken along the line 2—2 of Fig. 1;

Fig. 3 is a fragmentary elevational view, partly broken away, taken along the line 3—3 of Fig. 2;

Fig. 4 is an enlarged cross sectional view taken along the line 4—4 of Fig. 2; and

Fig. 5 is a transverse cross sectional view taken along the line 5—5 of Fig. 4.

The present invention may be utilized in connection with hand luggage of various types and consequently the luggage shown in Fig. 1 has not been illustrated in full. It is believed sufficient to state that the luggage includes a jaw frame 10 of suitable material and configuration. For instance, the frame may be generally U-shaped in

2

configuration and have a generally right angle cross section. In accordance with usual practice, it is also covered with a leather covering 12 to which the leather compartment defining portion 14 is stitched, as best illustrated in Fig. 2. The luggage includes also a partition 16 which is somewhat flexible in construction and which may be made of thin cardboard covered with a fabric and provided with a binding 18 around its periphery.

In accordance with the present invention, the partition 16 is adapted yieldably and releasably to be secured to the jaw frame by a pair of novel and easily manipulatable clasps. These clasps are of identical construction and, therefore, only the one at the left, which is indicated generally by the reference character 20, will be described in detail, although like reference numerals will be applied to the other clasp.

20 The clasp 20 includes a pair of relatively movable members of which the outer one, which is indicated by the reference character 22, will be called a casing member and of which the inner one, which is indicated by the reference character 24, will be called an attaching means or member. The inner attaching member is adapted to telescope into the outer casing member and the two members are urged into this telescoped condition by suitable resilient means such as the single spring 26 which is mounted and guided within the inner attaching member in a novel manner to be described shortly.

25 The inner attaching member is preferably attached to the partition near the upper end of the latter. It is preferred also that the attachment be by means of a leather strap 28 having a relatively long portion 30 stitched to the partition and narrower portion 32 looped through a slot 34 in the attaching member.

30 The slot 34 is preferably formed in a projecting and movement limiting enlarged portion 36 of the inner attaching member which is preferably generally trapezoidal in shape and forms an integral portion of the inner member. It forms an extension of a generally rectangular flat portion 38 slidably disposed within the casing member and which has a flange 40 at the end opposite the portion 36. The flange is dimensioned relatively closely to fit within the interior of the outer casing so that it may act as a guide. Additional guiding is provided by a flange 42 formed integral with the front wall 44 of the outer casing and which extends toward the portion 38 of the attaching member. The arrange-

ment is thus such that a narrow slot is provided for the portion 38.

The telescoping movement of the two parts is limited by the side walls 46 of the outer casing against which the shoulders 48 formed on the widened portion 36 of the attaching means abut, as best illustrated in Fig. 4.

The casing is provided with means whereby it can readily be attached to the frame. Its front wall 44 is provided with a narrow projection 49 having a hook 50 at its upper end. This hook is insertable into and held by a latch plate 52 having an aperture 54 and is secured to the bag frame jaw in suitable manner, as by a rivet 56.

The spring 26 is mounted within the clasp and guided in a simple and novel manner. The opposite ends of the spring abut against the flanges 40 and 42 on the inner and outer members, as best illustrated in Fig. 4. The end of the spring adjacent the flange 40 is guided by a pair of spaced apart flanges 60 punched out of the portion 38 of the attaching means. The end of the spring adjacent the flange 42 is secured by a tongue 62 punched out of the flange and extending axially of the spring.

From the foregoing detailed description of the present invention, it may be noted that the partition is easily releasably secured. The outer casing of the clasp can be grasped between the thumb and forefinger so that it can be moved against the force exerted by spring 26, thereby to move the hook 50 into alignment with the aperture 54 in the latch plate 52, either for the purpose of securing or releasing the partition. The clasp is neat in appearance, is self-adjusting, and is not likely to get out of order. Furthermore, the clasp itself is of a simple and novel construction and can be made and assembled economically.

It should be understood that while but a single embodiment of the invention has been illustrated and described in detail that these details are not intended to be limitative of the invention except in so far as set forth in the accompanying claims.

What I claim as new and desire to secure by Letters Patent of the United States is:

1. A clasp including an outer casing member having fastening means projecting from one end, a flange at the other end of said member extending from one side wall toward the other side wall a distance such as to leave a narrow slot adjacent the other wall, attaching means slidably and telescopingly mounted within said casing and having a portion projecting outside said casing through said slot, said attaching means having a flange at its housed end confronting the flange on said casing and abutting the interior of the casing, and spring means confined between said flanges for urging said casing member and attaching means into telescoped position, the flange on said casing having a tongue-like projection entering one end of said spring and said attaching means having a pair of flanges at least partly embracing said spring.

2. A clasp including an outer casing member having fastening means projecting from one end, a flange at the other end of said member extending from one side wall toward the other side

wall a distance such as to leave a narrow slot adjacent the other wall, attaching means slidably and telescopingly mounted within said casing and having a portion projecting outside said casing through said slot, said attaching means having a flange at its housed end confronting the flange on said casing and abutting the interior of the casing, and spring means confined between said flanges for urging said casing member and attaching means into telescoped position.

3. A clasp including an outer casing member having fastening means projecting from one end, a flange at the other end of said member extending from one side wall toward the other side wall a distance such as to leave a narrow slot adjacent the other wall, attaching means slidably and telescopingly mounted within said casing and having a portion projecting outside said casing through said slot, said attaching means having a flange at its housed end confronting the flange on said casing and abutting the interior of the casing, and spring means confined between said flanges for urging said casing member and attaching means into telescoped position, said projecting portion of the attaching means being enlarged to abut against said casing member and thus to limit the movement of said casing member and attaching means by said spring means.

4. A clasp including an outer member with spaced apart side walls, a flange at one end of said member extending from one side wall of said member toward the other side wall a distance such as to leave a narrow slot adjacent the other wall, an inner member slidably and telescopingly mounted within said outer member and having a portion at one end projecting outside said outer member through said slot, said inner member having a flange at its other end abutting said one wall of said outer member, and spring means confined between said flanges for urging said inner and outer members into telescoped position, one of said flanges having a tongue-like projection entering one end of said spring and one of said members having a pair of flanges extending longitudinally of and at least partly embracing said spring.
